Des. 199,285
Patented Sept. 29, 1964

199,285

COMBINED DRYER AND STACKER FOR PHOTOGRAPHIC MATERIAL OR SIMILAR ARTICLE

Daniel H. Robbins, Rochester, N.Y., assignor to Photostat Corporation, Rochester, N.Y., a corporation of Rhode Island

Filed Aug. 8, 1963, Ser. No. 76,152

Term of patent 14 years

(Cl. D61—1)

FIG. 1

Des. 199,285

PAGE 2

FIG 2

Des. 199,285

PAGE 3

FIG. 3

FIG. 4

FIG. 1 is a front, right-side perspective view of a combined dryer and stacker for photographic material showing my design;

FIG. 2 is a rear perspective view thereof;

FIG. 3 is a left side elevational view thereof; and

FIG. 4 is a top plan view thereof.

I claim:

The ornamental design for a combined dryer and stacker for photographic material, or similar article as shown.
